UNITED STATES PATENT OFFICE.

CHARLES F. HELLMAN, OF LOS ANGELES, CALIFORNIA.

TERMINAL CLAMP.

Application filed September 23, 1922. Serial No. 590,160.

The present invention relates to improvements in terminal clamps for electrical connections and is particularly designed to be used in connection with storage batteries used in automobiles although its use is not confined to that particular purpose. A particular object of the present invention is to provide a terminal clamp that may be easily and quickly attached and removed and still make a connection sufficiently rigid to give satisfactory results without the application of solder. A further object of the invention is to provide a terminal clamp that is interchangeable and may be used as a right-hand or a left-hand clamp.

With these objects in mind I have shown the preferred form of my invention in the accompanying drawing in which Figure 1 shows my clamp as connecting a heavy wire with the terminal of a battery, Figure 2 a plan view of my clamp as secured to the end of a heavy wire, Figure 3 a plan view of the same clamp turned so as to fit on a left-hand binding post, Figure 4 an end view of my clamp, Figure 5 a detail view of a split ring forming part of my clamp and Figure 6 a detail view of a slotted member used in my clamp. While I have shown only the preferred form of the invention it should be understood that various changes or modifications may be made within the scope of the claim hereto attached without departing from the spirit of the invention.

The battery (1) of which only a part is shown in the drawing, is provided with a conical binding post (2). My clamp (3) comprises a split ring (4) having a conical inner surface adapted to engage the conical outer surface of the binding post and terminates in two spaced lips (6) and (7), each lip being provided with an external groove (8). The two lips are adapted to be received in a slotted member (9) preferably U-shaped in form. The slotted member is sufficiently long to allow of the in-

sertion of the wire (11) between the groove (8) of one of the lips and one end of the slot. A set screw (12) is provided at the opposite end of the slotted member and is adapted to engage the groove (8) of the other lip and to force the two lips together so as to cause the ring to make a tight connection with the binding post. In tightening the two lips the set screw simultaneously forces the far lip into close contact with the wire so that when the set screw is tightened a contact is established between the wire and the binding post, so that the arms 6 and 7 are adapted to be held in a relatively permanent position on the yoke to prevent separation of the ring from the yoke.

It will be readily seen from the foregoing description that to adapt a right-hand clamp to a left-hand binding post it is only necessary to remove the split ring from the slotted member, turn the same over and return it, the two relative positions being shown in Figures 2 and 3.

I claim:

A terminal clamp for use in connection with the binding post of a storage battery comprising a yoke having a long slot, a split spring ring adapted to freely fit over the post embracing relation thereto, the ring having a pair of identical arms passing through the slot intermediate the ends thereof so as to provide a space between one arm and an adjacent end of the slot for the reception of a terminal wire, and a set screw adjustable in the yoke and passing into the slot to engage with the other arm so as to contract the ring and clamp it around the post and to crowd the arms with respect to the terminal wire to secure same in a relatively permanent position in the yoke and to prevent separation of the ring from the yoke when the ring is expanded and removed from the post.

CHARLES F. HELLMAN.
